BACKING PLATE FOR PULL AS USED ON DOORS, DRAWERS AND THE LIKE

David F. James, Torrance, Calif., assignor to Norris
Industries, Inc., Los Angeles, Calif.

Filed Aug. 9, 1973, Ser. No. 387,117

Term of patent 14 years

Int. Cl. D8—09

U.S. Cl. D8—179

FIG. 1.

FIG. 2.

FIG. 1 is a front elevation of a backing plate for pull as used on doors, drawers and the like, showing my new design; and

FIG. 2 is a side elevation thereof.

I claim:

The ornamental design for a backing plate for pull as used on doors, drawers and the like, as shown.
